UNITED STATES PATENT OFFICE

NATHAN BUEGELEISEN, OF NORWOOD, OHIO

DESIGN FOR A NOVELTY GOLF GAME TOY

Application filed August 1, 1932. Serial No. 44,507. Term of patent 3½ years.

To all whom it may concern:

Be it known that I, NATHAN BUEGELEISEN, a citizen of the United States, residing at Norwood, in the county of Hamilton and State of Ohio, have invented a new and original Design for Novelty Golf Game Toy, of which the following is a specification, reference being had to the accompanying drawing, forming a part thereof.

I claim:

The ornamental design for a novelty golf game toy as shown.

NATHAN BUEGELEISEN.
